A. K. SUTHERLAND.

SWITCH.

APPLICATION FILED OCT. 28, 1916.

1,226,404.

Patented May 15, 1917.

UNITED STATES PATENT OFFICE.

ALEXANDER K. SUTHERLAND, OF NEW BRITAIN, CONNECTICUT, ASSIGNOR TO THE TRUMBULL ELECTRIC MANUFACTURING COMPANY, OF PLAINVILLE, CONNECTICUT, A CORPORATION OF CONNECTICUT.

SWITCH.

1,226,404.

Specification of Letters Patent. Patented May 15, 1917.

Application filed October 28, 1916. Serial No. 128,321.

To all whom it may concern:

Be it known that I, ALEXANDER K. SUTHERLAND, a subject of the King of Great Britain, residing at New Britain, Connecticut, have 5 invented a new and useful Switch, of which the following is a specification.

My present invention relates particularly to rocking or oscillating switches of the push button type, and the objects of the invention 10 are to provide a switch of this character which will be more positive and certain in its action and particularly which will automatically lock at the end of each movement irrespective of any control attempted to be exercised on the push buttons or other operating medium. Other objects are to provide a 15 switch having these desirable characteristics which will be simple and sturdy in construction, will have a high current carrying capacity and will be relatively inexpensive of 20 production.

These objects I have accomplished in the main by a special construction of detent releasing mechanism embodying a detent releasing cam which is supported by and travels with the switch operating rocker but which has a special quick releasing detent-freeing movement imparted thereto independent of the movement imparted by the rocker. 25 This special detent releasing movement may be imparted to the cam by providing the same with dependent operating extensions which engage a dependent abutment on the contact carrying member.

Other features of the invention and details of construction will appear as the specification proceeds.

In the accompanying drawing I have illustrated my invention embodied in a practical 40 commercial form, but it will be understood that changes and modifications may be made without departing from the true spirit and scope of the invention.

In said drawing:

Figure 1 is a view in side elevation of the 45 switch mechanism as mounted in a suitable insulating base, the base here being in section.

Fig. 2 is a similar view taken on a plane 50 at right angles to the plane of Fig. 1.

Fig. 3 is a detail sectional view taken sub-

stantially on the plane of the line 3-3 of Fig. 2.

Fig. 4 is a detail sectional view taken substantially on the plane of the line 4-4 of 55 Fig. 2.

Fig. 5 is a view similar to Fig. 3 illustrating the latch releasing operation of the cam.

Considering the drawing now in detail:

10 designates an insulating base of typical 60 construction for the style of switch shown, this base being in the form of a hollow box, across the top of which extends a bridge or yoke-piece 11 which supports switch mechanism and forms a guide for the push buttons 65 12 and 13. 14 and 15 indicate the relatively stationary switch contacts suitably mounted in the base.

The movable switch contact, and the operating and controlling mechanism therefor 70 are mounted on the supports 16 dependent from the bridge piece.

17 designates the operating rocker to which the push buttons are connected, and the movable contact carrying member is 75 designated 18, these parts being mounted to rock on a pivot pin 19.

The movable contact is designated 20 and is shown suitably secured to the contact carrier and insulated therefrom by suitable insulation 21.

The contact carrier is shown provided with a detent portion 22 in the form of an upstanding T-shaped head, and is further shown provided with a dependent portion 85 23 with which one end 24 of the throwing spring 25 engages, the other end 26 of the throwing spring being engaged over a lug 26' on the operating rocker.

27 designates the latch or detent for the 90 contact carrier, the same being shown in the form of an outstanding lug 28 working in a guide slot 29 in one of the standards 16, said lug being carried by the slide 30 guided for vertical movement at the inner 95 side of the standard and normally pressed downward into holding engagement in front of the detent head by a spring 31.

The detent is released by a cam plate 32 having a cam track 33 on its upper edge 100 engaging a stud 34 on the detent slide and provided with laterally projecting lugs 35

at the opposite ends thereof bearing on top of the downwardly inclined opposite end portions 36 of the rocker. The detent slide is slotted at 37 to slide freely vertically over the pivot pin 19 and the cam is also provided with an elongated transversely extending slot 38 so that it can work freely over the pivot pin.

The cam plate is furthermore provided with dependent supporting extensions 39 near the opposite ends thereof and below the supporting lugs 35 which, as indicated in Fig. 5, are so disposed as to engage the dependent abutment portion 23 of the contact carrier.

In operation, pressure on the projected button (the one at the left in Fig. 1) swings the rocker on its pivot as indicated in Fig. 5, placing the throwing spring under tension in readiness to snap the switch contact as soon as the detent releases the same. During this rocking movement of the switch operating rocker, the cam is supported by and moves along with the rocker, the cam track thereon lifting the detent during this movement. Just prior to the releasing of the detent from the contact carrier, the dependent extension 39 at the lower end of the cam engages with the then stationary dependent abutment portion 23 of the carrier so that in the further continued movement of the rocker this lower end of the cam is supported by this abutment while the upper end of the cam fulfills crums on the supporting lug at that end of the cam. The independent movement of the cam thus obtained causes the detent to be snapped quickly from in front of the detent head on the contact carrier and, as the contact swings over, to drop quickly behind the other end of the detent head, positively locking the switch in its new position. The support 23 which serves to lift the lower end of the cam off the rocker, being carried by the switch carrier is snapped suddenly from under the cam by the throwing movement of the movable switch contact, and thus allowing the detent to fall freely back into its retaining position, deprives the operating buttons of any control over the detent and prevents the detent being held up out of its operative position by the manipulation of the buttons.

What I claim is:

55 1. In a switch of the character set forth, a rocking contact carrying member, a detent for said contact carrying member, an operating rocker, and a cam for freeing the detent from the contact carrying member supported by the rocker and normally rocking therewith and also having a movement independent of said rocker movement.

2. In a switch of the character set forth, a rocking contact carrying member, a detent for said contact carrying member, an operat-

ing rocker, a cam for freeing the detent from the contact carrying member supported by and movable with the rocker, and means for shifting said cam on the rocker to thereby impart a detent-freeing movement thereto in addition to the movement imparted thereto by the rocker.

3. In a switch of the character set forth, a rocking contact carrying member, a detent for said contact carrying member, an operating rocker, a cam for freeing the detent from the contact carrying member supported by and movable with the rocker, and means for shifting said cam on the rocker to thereby impart a detent-freeing movement thereto in addition to the movement imparted thereto by the rocker including an abutment disposed in the path of movement of the cam and arranged by engagement with said cam to produce a detent-freeing movement of the cam.

4. In a switch of the character set forth, a rocking contact carrying member, a rocker for operating the same, a detent for the contact carrying member, a cam disposed alongside the rocker and operatively engaging the detent, said cam having supporting lugs resting on the rocker and dependent operating portions extending below the rocker and an abutment disposed in the path of movement of the dependent operating portions of the cam.

5. In a switch of the character set forth, a rocking contact carrying member provided with a dependent abutment, a detent for said contact carrying member, an operating rocker and an operating cam for the detent supported on the rocker and having dependent portions for engagement with the dependent abutment of the contact carrying member.

6. In a switch of the character set forth, a switch operating rocker, a rocking contact carrier, a detent for said carrier, a cam for releasing said detent supported at opposite ends on said rocker and means for fulcruming said cam on said points of support at opposite ends of the rocker.

7. In combination, a rocking contact carrier having an upstanding detent portion and a dependent abutment portion, a detent engaging said detent portion, an operating rocker, and a cam for operating the detent supported by the rocker and having a dependent portion for engagement with the dependent abutment portion of the contact carrier.

8. In a switch of the character set forth, a switch operating rocker, a cam having lugs at opposite ends thereof bearing on opposite end portions of the rocker and dependent supporting extensions at opposite ends of the cam beneath said lugs, a rocking contact carrier, a detent for said carrier operated by the cam and means engaged by the depend-

ent supporting extensions of the cam in the rocking movement thereof.

9. In a switch of the character set forth, a pivot, a contact carrier mounted on said pivot, a detent for said contact carrier, a rocker mounted on the pivot having downwardly inclined opposite end portions and

a cam for operating the detent loosely engaged over the pivot and having supporting lugs at opposite ends thereof bearing on the 10 downwardly inclined opposite end portions of the rocker.

ALEXANDER K. SUTHERLAND.
